UNITED STATES PATENT OFFICE.

THOMAS J. CROSS AND JONATHAN STOUT, OF BELMORE, OHIO.

IRONING-BOARD.

SPECIFICATION forming part of Letters Patent No. 341,797, dated May 11, 1886.

Application filed April 17, 1884. Serial No. 128,269. (No model.)

To all whom it may concern:

Be it known that we, THOMAS J. CROSS and JONATHAN STOUT, citizens of the United States of America, residing at Belmore, in the county 5 of Putnam and State of Ohio, have invented certain new and useful Improvements in Ironing-Boards; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention consists in certain new and useful improvements in ironing-boards, the construction of the improvement being such that by means of an improved casting, which embraces the upper converging ends of one 20 pair of legs, and is pivotally connected to the table, the said converging legs will be braced rigidly relative to each other, but can afford the table, by means of said casting, the proper transverse bearing-support.

25 In the accompanying drawings, forming part of this specification, Figure 1 is a perspective view of our improved ironing-table. Fig. 2 is a plan view of the under side of the board, showing the legs folded within each other, and Fig. 3 is a detailed perspective view of the peculiar casting employed in our improved board.

A represents an ironing-board constructed in accordance with our invention, which is 35 provided near one end with ears *a a*, rigidly attached to the under side of said board and horizontally perforated.

B is the casting, which is provided at its three sides with a raised rim, B', adapted to 40 embrace the edges of the legs C C, and is also provided with arms B" B", which depend from the plate, so that the ends may engage with the perforations in the ears or lugs *a a*. The ends of the arms B" B" are reduced in diameter, so as to provide shoulders *b b*, which abut against the inner side of the ears *a a* and prevent a lateral movement of the legs. The longer supporting-legs, C C, converge toward 45 and are attached to each other at their point of junction, and are braced to each other at their lower ends by a cross-bar, *c*. A shorter

pair of legs, D D, of less width than the legs C C, are secured between the same by a central bolt, E, which passes through perforations in the parts, and is provided with a head and nut, which are located on the outer side of legs C C, as shown. The upper part of the shorter legs, D D, at their point of junction have attached thereto a plate, D', which engages with stops or bars *d d*, attached to the under side of the ironing-board. The lower portions of the shorter legs, D D, are connected to each other by a bar, *d'*.

In operating the device the legs are placed in the position shown in Fig. 1 when the board 65 is ready for use, and when it is desired to put the same away or fold it together, as shown in Fig. 2, it is only necessary to raise the ends of the board A, and the legs D D may be moved so as to occupy a position within the 70 legs C C.

By employing a peculiar form of casting B the legs C C, which converge toward each other, are rigidly embraced and held at their forward ends by said casting, which also enables the said legs to provide the necessary 75 transverse bearing-support for the board A.

We claim—

The combination, in an ironing-board, of a 80 table or board, A, having attached to its under side the depending ears *a a* and stops *d*, and the casting B, having side arms, B", to pivotally bear in said ears, and with the centrally-depressed portion, converging legs C C, having their front abutting portions secured 85 in said depression, converged legs D D, centrally pivoted within the legs C C, and provided at their converging ends with the plate D' for engagement with the stops *d*, the arrangement and construction being such that 90 the converging legs C C, while re-enforcing each other, afford a proper transverse bearing for the table A by means of the casting B, substantially as set forth.

In testimony whereof we affix our signatures 95 in presence of two witnesses.

THOMAS J. CROSS.
JONATHAN STOUT.
